UNITED STATES PATENT OFFICE.

PAUL KLIMOWICZ, OF STEVENS POINT, WISCONSIN.

CHANGEABLE WINDOW DISPLAY-SIGN.

1,305,121.

Specification of Letters Patent. Patented May 27, 1919.

Application filed August 13, 1917. Serial No. 186,028.

To all whom it may concern:

Be it known that I, PAUL KLIMOWICZ, a citizen of the United States, residing at Stevens Point, in the county of Portage

5 and State of Wisconsin, have invented certain new and useful Improvements in Changeable Window Display-Signs, of which the following is a specification.

My invention relates to display signs 10 sometimes known as "loose-letter signs," the letters being interchangeable so that the matter displayed may be varied *ad libitum*.

One of the objects of my invention is to provide a frame composed of interfitting 15 sections which may be united to form frames of different sizes. Another object is to provide letters or other characters and spacers which are reversible so that the characters upon either face may be employed or some of one face may be used 20 with some of the other face. The letters upon opposite faces may have different colors and the signs may be formed with a single color or with another color interspersed.

25 In the accompanying drawings, Figure 1 is a front elevation of an extensible frame with interchangeable letters embodying my invention; Fig. 2 is a transverse sectional view of a supplemental tongue and groove 30 member adapted to connect the frame and the letters along the top and at one side; Fig. 3 is a longitudinal sectional view of one of the letters; Fig. 4 is a transverse section of the same; Fig. 5 is a perspective 35 view of one of the frame sections; Fig. 6 is a perspective view of two of the sections united; Fig. 7 is a perspective view of one of the corner pieces; Fig. 8 is a diagrammatic view of the same showing the manner 40 of sliding the tenon; Figs. 9, 10 and 11 are sectional views taken respectively on the lines 9—9, 10—10, and 11—11 of Fig. 8; Fig. 12 is an illustrative view, partly 45 in section, showing the manner of connecting two letters when opposite faces are presented; Figs. 13 and 14 are side elevation and perspective views of a filler member; Fig. 15 is a perspective view of a tongue member which is necessary to connect 50 letters under certain circumstances; Figs. 16 and 17 are perspective views of a letter taken from opposite sides; Fig. 18 is a top plan view of the blank form used in constructing a letter; Fig. 19 is a plan 55 view of the blank form of the intermediate part of the letter block; Figs. 20, 20^a

and 20^b are plan views of blanks for forming a semicolon; and Fig. 21 is a perspective view of the filler piece shown in section in Fig. 2.

I construct the frame of corner and intermediate sections which interfit so that the dimensions of the frame may be varied as desired. Each of the intermediate sections, as shown in Fig. 5, is provided with 60 side panels 5 which may be ornamented in suitable designs, the opposite faces being executed in different colors if desired, or in different designs to correspond with the colors of the opposite faces of the letter 70 blocks. The opposite ends are provided with a tenon 6 and a mortise 7, which interfit when the sections are united. The inner side of each frame section is provided with a groove 10 to receive the tongues of 75 the letters. In order to hold the sections securely together I attach a flexible strip of suitable material 12 such as strong fiber-paper, to the outer side at one end, which projects and carries a sharp metallic point 14 80 which may be pushed into the adjacent section, the latter being preferably provided with a recess 15, to receive the end 12, so that the strip may be substantially flush with the edge of the section. 85

The corner sections are constructed in the manner illustrated in Figs. 7 to 11, inclusive. After the sections forming three sides of the frame have been connected together it would not be possible to insert 90 the last corner section if the tenon were rigid with the block section. I, therefore, construct the corner section with a separate tenon 6^a which is attached to a separate end piece 16, the tenon sliding through a 95 recess extending from end to end through the section. The flexible strip 12 is made longer than the corner block and slides through staples 17 which hold it in position, one end being secured to the end-piece 100 16 and the other end projecting and carrying the metallic point 14.

By referring to Fig. 1 it will be evident that the frame sections may be fitted together by means of their tenons and mortises beginning with the section marked 1 at the upper left hand side and continuing entirely around the frame to the last intermediate section marked 1^x at the left end of the upper side. As previously stated, 110 it would not be possible to insert the closing corner block 1^x if the tenon were rig-

idly secured thereto. In order to place this closing corner section in position it is necessary to withdraw the tenon 6^a until its end is flush with the edge of the section 5 block by pulling out the end-piece 16 in the manner illustrated in Fig. 7 and shown in dotted lines in Figs. 8 and 9. The corner section may then be placed in position with the tenon of the last upper section 1^x entering 10 the mortise in the corner section. The end piece 16 may then be pushed into its normal position against the corner section block, thereby pushing the tenon 6^a into the mortise in the upper end of the 15 first intermediate section 1. By then pushing the metallic point 14 of the corner into the first intermediate section, the frame sections will be rigidly secured together so that the frame may be handled as an integral 20 rigid structure. The dimensions of the frame may be changed at any time by withdrawing the metallic points or contacts 14 to thereby permit the sections to be separated for the withdrawal or insertion 25 of sections as may be desired.

The letter blocks or characters are constructed in a manner permitting them to be fitted into the sign so that the joints between the letters will not be observed, the completed 30 sign having the appearance of being painted upon an integral or solid background. For this purpose I construct them in the form shown in Figs. 16 and 17 showing opposite faces of the same character. The letters upon opposite faces may be executed in different colors as I have indicated by the longitudinal and transverse shading or cross-hatching. Thus the letter in Fig. 35 16 may be red while that on the opposite face shown in Fig. 17 may be blue.

In order that the letters may be fitted together in making up a sign with either face uppermost or with some having one face uppermost interspersed with others having the opposite face uppermost I construct the letter blocks in the manner shown in longitudinal section in Fig. 3 and in transverse section in Fig. 4.

Each letter may be formed of eight pieces 50 of material. The pieces 20, 20', 21, 21' and 23 are rectangular, 20 and 20' being preferably of cloth-board, while the pieces 21, 21' and 23 may be of straw-board. The piece 24 which is folded around the central piece 55 23, may be made of heavy paper of cheap grade. The piece 25 may also be made of a cheap grade of paper half the thickness of 24 and is cut in blank form shown in Fig. 19, and then folded about the pieces 21, 21' 60 and 23 in the manner shown in Figs. 3 and 4. The pieces 20 and 20' are then pasted in the position indicated, after which the outer covering piece 26, cut in blank form shown in Fig. 18, is folded over the previously 65 formed block as indicated, with the edges

projecting at one side 26^a and at the top end 26^b. It is to be understood that the pieces are glued together and when completed form the letter blocks shown in Figs. 16 and 17. For convenience in selecting the letters when 70 the blocks are packed in boxes and file cases, a small letter corresponding to the character on the faces of the block may be placed on the blank in the positions indicated so that they will appear upon the edges of the 75 tongues on one side and end as illustrated in Figs. 16 and 17. It will be observed that the letters constructed in the manner described provide a central tongue along one side and end and a central groove along the other side 80 and end.

In placing the letters in the frame, it will be evident that the two projecting tongues upon either side of the central groove at the bottom of the letter will fit into the groove 85 in the inner side of the sections of the frame and that the corresponding projecting tongues upon one side of the letters will fit into the groove upon one side of the frame. If the letters are used with the 90 face shown in Fig. 16 uppermost, then the right hand side of the letters will fit into the groove at the right of the frame; but if the opposite face of the letter is uppermost as illustrated in Fig. 17, then the double 95 tongues on the left side of the letter block will fit into the groove at the left of the frame. It is necessary to use a filler strip at one side of the frame and at the top of the frame. This filler strip may be in the 100 form shown in Fig. 21 and constructed of built up strips pasted together in the manner illustrated in cross-section in Fig. 2. The filler strip 30 connects the letter on the central tongue side and the frame by fitting 105 over the tongue of the letter and into the groove of the frame in the manner clearly illustrated in the dotted line construction of Fig. 2.

When the letters having the same faces uppermost and therefore of the same color are fitted together in making up the sign, the central tongue on one side will fit into the groove in the side of the adjacent meeting letter, these parts fitting very accurately 115 which is important in order that the sign may hold together when set up. The overhanging portions of the pieces 20, 20' slide over the depressed portions 26^c at the margins of the letters to the overhanging edges 120 26^a fitting neatly against the slanting shoulder portions 26^e so that the top surface 26 of one letter is continuous with that of the adjoining letter. In order to render the juncture lines between the letters still less 125 noticeable and practically invisible I provide the background of the letters with a graining which simulates the graining of wood by providing a series of closely drawn vertical and horizontal lines which I make 130

more dense at the top, bottom and center of the letters, as illustrated at the left hand part of Fig. 18. This increased density of lines is not half as long at the ends as at the center. In this manner the denser shadings at the ends of the two letters which abut end to end, unite to form a shaded area equal to that at the center of the letter. The vertical shade lines of this graining mask and 10 make invisible the junctures at the meeting vertical lines between letters while the horizontal lines mask the horizontal junctures of the letters. In this manner I am enabled to completely hide the lines between adjacent 15 letters so that the completed sign appears to be integral or as if painted upon a solid unbroken background.

It will be observed that each letter block is provided with a notch or cut-away portion 32 at diagonally opposite top and bottom corners. This is for the purpose of permitting the overhanging edges at the tops of one line of letters to overlap the depressions at the bottoms of the letters in the next 25 line above, without interfering with each other. When the letters having the same corresponding faces uppermost are fitted together in the manner above described, the tongues at the top edge of one line of letters will fit into the grooves in the bottom edge of the letters in the line next above, with the overhanging portions 20, 20' sliding over the depressed portions 26^a and the overhanging edges 26^b of the top sheet abutting 30 the slanting shoulders 26^c of the adjacent letters. There will be no overlapping of the overhanging parts at the corners because of the notches or cut-away portions 32 as will be evident.

40 When it is desired to use letters with opposite faces adjacent each other, as for instance where it is desired to introduce a blue letter in a line of red letters, the grooves of adjacent letters will face each other on 45 one side and the tongues of adjacent letters will face each other upon the other side. Thus if the letter shown in Fig. 16 having the red letter uppermost is to be joined to the blue letter shown in Fig. 17, the two grooved 50 edges will come together so that they will not interfit. It is necessary, therefore, to connect the letters in the manner illustrated in Fig. 12 by inserting an auxiliary tongue member 34 into the abutting grooves 55 of the two letters to form a connecting link. It is also necessary to fill in the depressed portions 26^c which come together and for this purpose I provide a filling member 35 shown in Fig. 14 which is provided with a 60 depending lug 36 adapted to fit down into the adjacent notches 32 at the top edges of the letters, this member being formed with an under backing piece 37 adapted to fill in the depressed portions 26^c and the overhang- 65 ing edges of the top piece 35 abutting the in-

clined shoulders 26^c so that the top surface 35 is flush with the top surfaces 26 of the adjacent letters. The upper piece 35 is also provided with a depressed portion 35^a adapted to conform to the depressed portions at the 70 bottom ends of the letters. The upper surface of the filler member 35 should be provided with the shading or graining to conform to the background of the letters in order to completely hide the juncture with 75 the letters in the manner previously described.

Character blocks of different widths may be constructed in the manner previously described. Thus in Figs. 20, 20^a and 20^b I 80 have shown the form of the blanks corresponding to the pieces 26, 24 and 25 respectively of Figs. 3 and 4 and proportioned in a manner suitable for the construction of a semi-colon, the parts being merely made 85 narrower than for the letters.

It is sometimes desirable to form an inner border within the body of the sign for the purpose of ornamentation to surround a central part of the contents of the sign. 90 For this purpose I construct bar members in the same manner as the letters are formed by cutting blanks similar to those illustrated in Figs. 20, 20^a and 20^b to be used as vertical ornamental strips and I also construct those 95 to be used horizontally in the same manner except that the longer dimensions extend horizontally and the vertical height is contracted correspondingly, the resulting horizontal bar being illustrated at 40 in Fig. 1 100 and the vertical bars being illustrated at 41. These are fitted together in the same manner as previously described in connection with the letters.

It is sometimes desirable to set up signs of 105 smaller dimensions for which the frame sections would seem too heavy or massive. In such cases I employ the ornamental bars 40, 41 to form the frame and supply it on two sides with the supplemental tongue and groove members 30 illustrated in Figs. 2 and 21, these members being provided with an outer shallow groove 33 which serves to retain a cord or wire which may be tied around the frame to combine the parts securely together.

The advantages possessed by the various 110 novel features of my changeable window display sign will be especially appreciated by those who have had experience in designing and executing display signs to suit varying conditions. The interchangeable frame members permit the frame to be extended to any desired dimensions or to be correspondingly contracted with facility and without 115 requiring any cutting or fitting or the use of any tools. The double-faced reversible letters which may be made in different colors enable one to readily interchange and vary 120 the color scheme of any portion of the sign 125 130

- to make it more attractive or for the purpose of emphasizing any feature in the sign. Interfitting tongue and groove connections render the sign structurally quite rigid, enabling it to be handled without difficulty. My method of practically obliterating the lines of juncture between the letters, thereby giving the effect of a solid or integral background, so that the letters appear to be formed or painted upon a solid backing overcomes the usual piece-meal appearance of signs which are made up of separate letter blocks and presents an exceedingly attractive appearance.
- 15 I have described in detail the particular construction illustrated in the accompanying drawings for the purpose of disclosing an embodiment of my invention but it is to be understood that various changes and modifications may be made within the scope of my claims and without in any manner departing from my invention.
- I claim:
1. A changeable window display sign, comprising a frame having sides consisting of a plurality of interchangeable sections, each having means for engaging with adjacent sections and locking means for preventing disengagement.
  2. A changeable window display sign, comprising a frame having sides consisting of a plurality of interchangeable sections, each having a tenon at one end and a mortise recess at the other end, and a securing device adapted to prevent disengagement with the adjacent section.
  3. A changeable window display sign, comprising interchangeable frame sections each having a tenon at one end, and a corner section having a movable tenon member.
  4. A changeable window display sign, comprising interchangeable frame sections adapted to be connected to form a frame of any desired dimensions, and provided with a groove upon the inner side, rectangular character blocks having a tongue upon one side and an end and a groove upon the other side and end, the tongue of one block being adapted to engage the recess in any other block, one end and side being adapted to engage the grooves in the frame sections, and auxiliary grooved members adapted to engage the tongues of the blocks and the grooves in the frame to connect the other side and end of the blocks therewith.
  5. In a changeable display sign, interchangeable reversible character blocks, each having a tongue along one side and one end and a groove along the other side and end, the face of the block having a marginal de-

pression along the grooved edges, and an overhanging flexible margin along the edges having a tongue, the flexible margin upon one block being adapted to abut the inner edges of the depressed margins of the adjacent block to thereby form an unbroken surface in the plane of the characters.

6. In a changeable display sign, interchangeable reversible character blocks, each having a tongue along one side and one end and a groove along the other side and end, the face of the block having a marginal depression along the grooved edges, and an overhanging flexible margin along the edges having a tongue, the flexible margin upon one block being adapted to abut the inner edges of the depressed margins of the adjacent block when the tongue of one block engages the groove of an adjacent block having the same face, and a filler member adapted to bridge the depressions in adjacent blocks when adjacent blocks having opposite faces abut with their grooved sides juxtaposed.

7. In a changeable display sign, interchangeable reversible character blocks, each formed of a plurality of superposed layers of fibrous material, said layers being arranged to provide a central tongue along one side and end, and a central groove along the other side and end, and an outer envelop or sheath covering the opposite faces and the grooved edges of the block.

8. In a changeable display sign, interchangeable character blocks having interfitting edges, and means for masking or rendering inconspicuous the juncture between adjacent blocks consisting in providing a network of intersecting lines upon the faces of the blocks at the ends and intermediate thereof, said lines being substantially parallel to the edges of the block.

9. In a changeable display sign, interchangeable character blocks, and means for masking or rendering inconspicuous the juncture between adjacent blocks consisting in providing a network of intersecting lines upon the faces of the blocks at certain portions thereof, said lines extending adjacent to the edges of the block.

10. In a changeable display sign, interchangeable character blocks, and means upon the face of each block for rendering the edges of adjacent blocks less conspicuous.

In testimony whereof I affix my signature in the presence of two witnesses.

PAUL KLIMOWICZ.
